J. W. COSGROVE

CEMENTING APPARATUS

Filed June 26, 1920

UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

CEMENTING APPARATUS.

Application filed June 26, 1920. Serial No. 391,983.

To all whom it may concern:

Be it known that I, JOHN W. COSGROVE, a citizen of the United States, residing at Medford, in the county of Middlesex and 5 State of Massachusetts, have invented certain Improvements in Cementing Apparatus, of which the following description, in connection with the accompanying drawings, is a specification, like reference characters on the drawings indicating like parts in the several figures.

This invention relates to apparatus for the application of cement. It is especially adapted for thus coating portions of shoes, 15 as the bottom and foxing areas, preparatory to laying the soles. Work of this character is done by experienced hand operators at a speed and with an accuracy that renders unpromising the successful employment for 20 this purpose of machines at all complicated or difficult to maintain, or those which are slow to operate.

With such conditions in view, an object 25 of the present invention is to provide a simple apparatus by which the work may be operated upon rapidly and with uniform results. For this purpose, I employ a brush having fibers radiating about an axis, the ends of which fibers furnish an applying 30 surface inclined longitudinally of the axis to correspond generally to the form of the surface to be coated, the arrangement being such that the applying face substantially corresponds to the transverse contour of that 35 area of a shoe upper to which the foxing strip is to be applied. With this brush is associated a gage member having its edge adjacent to the ends of the fibers at the extremity of the brush and arranged for contact with the surface to be cemented. With 40 such an organization, a simple movement of the work past the brush properly supplied with cement applies the desired coating. The operation may further be simplified by 45 associating with the foxing-cementing brush, or other applying member, a bottom-cementing member having an upwardly extending surface, here shown as approximately plane, by which the coating of the shoe bottom is 50 effected simultaneously with that of the foxing area. This last-mentioned brush may also serve as a bottom rest to position the work with relation to the foxing-cementing brush.

Another object of the invention is to arrange for the maintenance of the apparatus in good operating condition and so that it shall act advantageously for work having the areas to be coated differently related. In accomplishing this, the inclined brush is 60 preferably arranged to have its applying surface fixed in different positions about its axis. By this expedient, a fresh applying surface may be presented when the fibers become worn. The companion brush, which 65 is best arranged with its applying surface substantially at right angles to the axis of the inclined brush, is fixed for adjustment longitudinally of said axis. This adjustment may be resorted to when the bottom- 70 cementing brush becomes worn, and also adapts the apparatus for cementing different heights of foxing areas.

It is an additional object of the invention to supply the cement effectively to the applying means. This I prefer to do positively and in controllable quantities. To this end, the applying member has a cement-delivering passage, and to this passage cement is supplied through an intermediate conduit. 80 In the conduit is a member movable both to close it to cut off the supply to a plurality of applying members, as those acting upon the foxing area and upon the shoe bottom, and to exert pressure to force a portion of 85 the cement through the delivering passage.

Hereinafter other objects will be developed, reference being had to the accompanying drawing, in which

Fig. 1 is a perspective view of one embodiment of my improved cementing apparatus;

Fig. 2 is a central vertical, longitudinal section therethrough; and

Fig. 3 is a vertical sectional detail through another form of the apparatus.

Upon a suitable frame 10 is mounted a cement container 12, from which the contents may flow by gravity through a conduit or passage, shown as provided in the container and frame. This conduit, below 100 the container, is first vertical at 14, and from this vertical portion it extends horizontally at 16, opening through the side of the frame. The flow may be controlled in the conduit by a valve 18 arranged for rotation to open 105 and close the passage, and having an actuating lever at the side of the apparatus. About the opening of the portion 16 through

the frame is arranged a circular recess 20 concentric to the openings. Seated in the recess is an applying member A, here shown as a brush having a cylindrical body 22 fitting the recess at its inner end, from which body radiate bristles or like flexible fibrous members 24. The applying surface 27 of the brush at the ends of the fibers is preferably frusto-conical, the inclination being shown as approximately the form of the surface to be coated. When a foxing area of the upper of a shoe is to be cemented by its travel longitudinally along the brush, this inclination may be between the rather flat transverse contour of such area at the shank portion and the more nearly vertical outline which approaches its extreme at the toe and heel portions. The flexibility of the fibers permits them to exactly conform to the work with little effort on the part of the operator, they yielding to a greater extent at one or both of the outer edges when the shank portion is operated upon and at the center for the ends of the heel and toe. The brush is normally fixed in position in the recess by a screw 26, preferably having a conical point entering a corresponding recess in a disk 28. At the center of this disk is a boss 30 lying in an axial opening 32 at the center of the brush and alined with the portion 16 of the cement conduit. The retaining screw 26 is threaded through an arm 34 fixed vertically on a bracket 36 overhanging the brush. As herein illustrated, the fibers of the brush radiate about its entire periphery, and this allows it to be rotated through 360 degrees to present fresh portions at the working points when other portions become worn. This, however, is not essential, and obviously the brush may be made of some less circumferential dimension. The periphery of the disk 28 is inclined at 38 to a sharp edge, which lies in proximity to the extremities of the brush fibers at the outer or smaller end. The relation of the disk is such that as the work is passed beneath the brush, the reduced edge will come in contact with it, furnishing a gage to determine the line of the edge of the cemented area, and tending, by its position between the brush and the portion of the work which is to remain uncoated, to prevent the flow of cement outwardly over the latter. Surrounding the inner extremity of the body of the brush and bearing against the adjacent wall of the frame is a disk 37, which acts as a barrier to the flow of cement in this direction. Passing through the body of the brush from the opening 32 to points between the fibers are passages 40 for the delivery of cement from the conduit to the applying surface. These passages, as shown, are formed about the entire body, but, since only the lower portion of the brush is used at any particular time, to prevent

flooding of the upper unused section plugs 42 are inserted in the openings of this idle portion. When the brush is rotated to bring a fresh applying section into position, the plugs are removed from the corresponding openings and inserted in those which are carried to the inactive position.

I prefer to deliver cement from the container to the applying surface under the influence of a positive feeding force and in definite quantities. For this purpose, a rearward horizontal extension 44 of the portion 16 of the cement conduit contains a plunger-valve 46, to the outer end of which is articulated a bell-crank lever 48 fulcrumed upon the frame. Pivoted to the opposite arm of the bell-crank is a rod 50 joined to a treadle, which does not appear in the drawing. At the forward end of the plunger is an upwardly inclined surface 52, forming a reduced edge movable across the conduit portion 14. Normally, the lever is held back against an adjustable stop-screw 53, the plunger at this time being at the right of the conduit portion 14, as viewed in Fig. 2 of the drawings, to open said conduit and permit the portion 16 and connected passages to fill with cement from the container. When the operator depresses the treadle, the plunger moves across this portion 14, the reduced edge cutting the cement and decreasing the tendency to force it back toward the container; and then, as the closure of the upper part of the conduit is completed, exerting pressure upon the charge of cement contained in the horizontal portion 16, and forcing it through the brush passages 40 and between the fibers to the applying surface. This operation may be repeated as frequently as is necessary to maintain upon the applying surface the desired quantity of cement.

Simultaneously with the coating of the foxing area of a shoe, the bottom may also be cemented. To accomplish this, there is mounted below and adjacent to the inner edge of the applying member A a member B having a rectangular body 54 and projecting fibrous material 56. These constitute a brush, which preferably has a substantially plane applying surface 58, shown as lying approximately at right angles to the axis of the member A. The brush B is carried upon a base 60, from the rear of which a horizontal spindle 62 projects into a socket 64 in the frame, in which it is secured by a set-screw 66 threaded into the frame. The brush may be adjusted by loosening the set-screw and moving said brush either forwardly or rearwardly beneath the brush A to compensate for the shortening of the fibers 56 by wear, or to provide for cementing to different heights by the brush A. The latter function may be fulfilled because the brush B serves as a bottom rest,

- holding the work against transverse movement beneath the brush A, and determining the position of its outer or gage-edge thereto. Aiding in this positioning effect are 5 stop-pins 68, of which two are here illustrated, located symmetrically at opposite sides of a horizontal axis and near the center of the brush B. These both limit the movement of the work across the brush A 10 by their contact, and also determine the depth to which said work may be forced into the bristles of the brush B, so that this will act most effectively in the application of cement. 15 As illustrated in Fig. 2, cement is delivered to the brush B under the control of the valve 46. To provide for this, the base 60 is formed with a compartment 70, serving as a receptacle from which cement may 20 flow through passages 72 formed in the body 54 between the bristles, and generally corresponding in relation and function to the passages 40 of the brush A. The top of the compartment 70 is open at 74 and about this opening the brush base fits closely against a horizontal wall 76 of the frame, preventing the leakage of cement at this point. To this opening 74 cement is delivered 25 from the conduit portion 16 by a downward vertical extension 78. This supplies cement to the compartment 70 when the valve 46 is open, and receives pressure upon the closure of said valve to force the cement through the brush passages 72. The opening 74 is enough wider horizontally than the portion 78 of the conduit to enable the latter to deliver cement to the former in all 30 adjusted positions of the brush B. 35 In using the apparatus for cementing the foxing areas and bottoms of lasted shoes, one of which is illustrated at S, the brush B is so adjusted in a horizontal direction, by means of the set-screw 66, that the distance between the vertical lines through the 40 ends of the pins 68 and the gage-edge of the disk 28 will substantially equal the height of the foxing area upon the particular work to be operated on. The operator 45 actuates the valve 46 by the treadle to deliver charges of cement from the container through the conduit and delivery passages of both brushes to their applying surfaces, and then holding a shoe in his hands and 50 pressing it against the ends of the fibers 56, as limited by the pins 68, turns it rapidly beneath and forces it against the brush A until the entire circumference of the foxing area has received cement from the brush 55 A and the bottom has been coated by the brush B. It should be noted that this last-mentioned brush is of such height vertically that it does not operate across the entire width of the shoe bottom; but its vertical 60 dimension is sufficient to carry it below the longitudinal axis of the shoe, so that in the rotation of the work the entire surface is coated. The operations upon successive pieces of work are continued in the same manner, it only being necessary occasionally 65 to replenish the cement in the container and to adjust the brushes A and B to maintain the applying surfaces in correct relation to the work and in proper condition for applying the cement. 70 If desired, the means for separately supplying cement from the conduit to the brush B may be omitted. As appears in Fig. 3, the body of this brush is mounted upon a 75 solid base 80 guided at the upper edge for 80 adjustment, as in the form of apparatus just described against an overhanging frame wall. By the capacity of the conduit or by the frequency with which the cement is supplied through the operation of the valve 46, 85 an excess over the requirements of the brush A is delivered thereto, and this flows down over the applying surface of the brush B to deliver its charge. The apparatus otherwise may be generally the same as 90 that already described. 95 Having thus described my invention, what I claim as new and desire to secure by Letters Patent of the United States is:
1. In a cementing apparatus, a cement applying brush provided with fibers radiating about an axis and having an applying surface furnished by the ends of the fibers inclined longitudinally of the axis to correspond generally to the portion of the work to be coated, a gage member having an edge adjacent to the fibers at the extremity of the brush and arranged for contact with the surface to be cemented, a cement container, and a conduit arranged to deliver cement from the container outwardly between the brush fibers. 105
  2. In a cementing apparatus, a member having a curved applying surface inclined with respect to its axis, a gage arranged for contact with the surface to be cemented at the end of the applying surface nearest the axis and with its contact-portion substantially coinciding with said end of said applying surface, and means for supplying cement to the applying surface. 110
  3. In a cementing apparatus, a frustoconical brush, a gage-disk co-operating with the end of the brush which is of smallest diameter, with its periphery substantially coinciding with the extremities of the brush-fibers at said end and contacting with the surface to be cemented, and means for supplying cement to the brush. 120
  4. In an apparatus for cementing shoes, a brush having the ends of its fibers inclined to correspond generally to the transverse contour of the foxing area, a bottom-cementing brush situated adjacent to the foxing-cementing brush and with the ends 125 130

- of its fibers presenting an approximately plane surface, and means for supplying cement to the brushes.
5. In a cementing apparatus, a brush having a conical applying surface, a co-operating brush having an approximately plane applying surface, and means for supplying cement to the brushes.
10. In a cementing apparatus, a brush having a conical applying surface, a co-operating brush having an approximately plane applying surface lying substantially at right angles to the axis of the conical brush, and means for supplying cement to the brushes.
15. In a cementing apparatus, a cement-applying brush provided with fibers radiating about an axis and having an applying surface furnished by the ends of the fibers inclined longitudinally of the axis to correspond generally to the portion of the work to be coated, means arranged to fix the brush in different applying positions about its axis, and means for supplying cement to the brush.
20. In an apparatus for cementing shoes, a brush having the ends of its fibers inclined to correspond generally to the transverse contour of the foxing area, a bottom-cementing brush situated adjacent to the foxing-cementing brush and with the ends of its fibers presenting an approximately plane surface, means arranged to change the relative positions of the brushes, and means for supplying cement to the brushes.
25. In an apparatus for cementing shoes, a brush having the ends of its fibers inclined to correspond generally to the transverse contour of the foxing area, a bottom-cementing brush situated adjacent to the foxing-cementing brush and with the ends of its fibers presenting an approximately plane surface, means arranged to permit the bottom-cementing brush to be adjusted in position along the foxing-cementing brush, and means for supplying cement to the brushes.
30. In a cementing apparatus, a brush having a conical applying surface, a co-operating brush having an approximately plane applying surface lying substantially at right angles to the axis of the conical brush, means arranged to permit said co-operating brush to be adjusted longitudinally of the axis, and means for applying cement to the brushes.
35. In a cementing apparatus, a brush having a conical applying surface and being mounted to rotate about its axis, means arranged to fix the brush in different angular positions, and means for supplying cement to the brush.
40. In an apparatus for cementing shoes, a brush arranged to operate upon the foxing area, and a bottom-cementing brush situated adjacent to the foxing-cementing brush and arranged to serve as a bottom rest for the work to position it with relation to the foxing-cementing brush.
45. In an apparatus for cementing shoes, a brush having the ends of its fibers inclined to correspond generally to the transverse contour of the foxing area, a bottom-cementing brush situated adjacent to the foxing-cementing brush and with the ends of its fibers presenting an approximately plane surface, movement-limiting means for the work associated with the bottom-cementing brush, and means for supplying cement to the brushes.
50. In an apparatus for cementing shoes, a brush having the ends of its fibers inclined to correspond generally to the transverse contour of the foxing area, a bottom-cementing brush situated adjacent to the foxing-cementing brush and with the ends of its fibers presenting an approximately plane surface, stop-pins situated between the fibers of the bottom-cementing brush, and means for supplying cement to the brushes.
55. In an apparatus for cementing shoes, a brush having the ends of its fibers inclined to correspond generally to the transverse contour of the foxing area, a bottom-cementing brush situated adjacent to the foxing-cementing brush and with the ends of its fibers presenting an approximately plane surface, stop-pins situated between the fibers of the bottom-cementing brush, and means for supplying cement to the brushes.
60. In a cementing apparatus, a cement-applying member provided with a cement-delivering passage, a cement container, a conduit having a portion opening into the container and a portion lying at an angle thereto and communicating with the delivering passage, and a valve member movable in the last-named portion of the conduit and having an inclined edge adjacent to the first-mentioned portion of the conduit.
65. In a cementing apparatus, a plurality of cement-applying members each provided with a cement-delivering passage, a conduit leading from the container and connected to the delivering passages of both applying members, and a movable member arranged to close the conduit to cut off the supply of cement from the container and to force cement through the delivering passages to both applying members.
70. In a cementing apparatus, a cement-applying member provided with a cement-delivering passage and being variable in position, a cement container, and a conduit connecting the container and delivering passage and having a portion movable with the applying member.
75. In a cementing apparatus, a plurality of cement-applying members each provided with a cement-delivering passage, means arranged to permit one of the applying members to be varied in position with relation to the other, a conduit leading from the container and connected to the delivering passages of both applying members, a portion of the conduit being movable with the variable applying member, and a movable member arranged to close the conduit to cut off the supply of cement from the container and to force cement through the de-

livering passages to both applying members.

19. In a cementing apparatus, a frame provided with a recess and a passage opening into the recess, a cement container de-

5 livering to the passage, a brush having a body seated in the recess and a passage through the body communicating with the frame-passage and terminating between the brush fibers, said fibers radiating from the 10 axis of the recess and frame-passage, and means for holding the brush in the recess.

20. In a cementing apparatus, a frame provided with a recess and a passage opening into the recess, a brush having a body 15 seated in the recess and a passage through the body communicating with the frame-passage and terminating between the brush fibers, and a gage-plate extending across the end of the brush opposite the frame.

21. In a cementing apparatus, a frame provided with a recess and a passage opening into the recess, a valve-plunger movable in said passage, a cement container delivering to the passage, a brush having a body 25 seated in the recess and a passage through the body communicating with the frame-passage and terminating between the brush fibers, and means for holding the brush in the recess.

22. In a cementing apparatus, a frame provided with a passage therethrough, a cement container delivering to the passage, a receptacle arranged for adjustment upon the frame and to receive in its various positions cement from the passage, said receptacle including a brush having passages

opening between the brush fibers and into the receptacle, and means arranged to fix the receptacle in its adjusted position.

23. In a fluid-applying apparatus, an 40 applying member, a work-rest having an upwardly extending work-engaging surface, said applying member and work-rest being arranged for relative adjustment, and means arranged to deliver to the work-engaging 45 surface the fluid to be applied.

24. In a coating apparatus, a plurality of applying members arranged for independent movement, and a reservoir located above the applying members and having an 50 outlet delivering to a passage individual to each applying member.

25. In a foxing and bottom-cementer for shoes, an applying member for co-operation with a foxing area, an applying member for 55 co-operation with a shoe bottom, said members being arranged for independent adjustment, means for fixing the members independently in their adjusted positions, and means for independently supplying cement 60 to the members.

26. In a foxing and bottom-cementer for shoes, an applying member for co-operation with a foxing area, an applying member for co-operation with a shoe bottom and being 65 constructed and arranged with respect to the foxing area to serve as a work-rest during foxing cementing, and means for supplying cement to the applying members.

In testimony whereof I have signed my 70 name to this specification.

JOHN W. COSGROVE.
